UNITED STATES PATENT OFFICE.

THOMAS H. FARNHAM, OF BOSTON, MASSACHUSETTS, ASSIGNOR TO THE UNION CARPET LINING COMPANY, OF SAME PLACE.

MACHINE FOR FOLDING CARPET-LININGS.

SPECIFICATION forming part of Letters Patent No. 270,940, dated January 23, 1883.

Application filed October 22, 1880. (No model.

To all whom it may concern:

Be it known that I, THOMAS H. FARNHAM, of Boston, in the county of Suffolk and State of Massachusetts, have invented a new and 5 useful Improvement in Machines for Folding Carpet-Linings, of which the following is a specification.

The nature of my invention consists in combining with a carpet-lining sewing-machine, 10 or with any machine for performing similar work, a device for forming in the work, as it is delivered, creases alternately reversed, the creases being formed at each half-yard or at any other desired interval, the devices for 15 forming one crease consisting of a hollow V-shaped die, which fits on to a wedge shaped die, while the dies which form the alternating crease consist of a hollow V-shaped die, into 20 which a wedge-shaped die is forced, these two sets of dies working alternately, so as to give the required reversed creases at some predetermined definite intervals.

In the drawings, Figures 1 and 2 represent elevations showing a part of the sides of a 25 carpet-lining sewing-machine. Fig. 3 is a plan showing a part of the carpet-lining machine. Fig. 4 is a sectional and perspective view, showing the leading feature of my invention.

30 Let A A' A², Figs. 1, 2, and 3, represent the sewing mechanism, which is in this case a series of needles and loopers and their operating devices, constructed on the well-known plan of the Willcox & Gibbs sewing-machine.

35 B is the fabric operated upon, in this case carpet-lining. The fabric B passes under the sewing mechanism A A' A² to the drawing feed-rolls D D', the feed-roll D being operated by a ratchet, E, pawl E', eccentric-link E², and eccentric F, which is driven from the sewing-mechanism gear, as shown in Fig. 2. As the finished fabric B' passes out from the drawing-rolls it goes between the dies H H' and K K'. (See Figs. 1 and 4.) At a proper 40 time the die H is thrown down onto the fabric, 45

and, in combination with the lower die, H', creases it, as indicated in Fig. 4, so that it may readily fold as it passes out of the machine. The crease made by the dies H H' forms the fold at b², while the crease formed by the dies K K' makes the fold b'. These dies are operated alternately by the pin at D³, Fig. 1, which is connected with the lower feed-roll, D', as shown in Fig. 1, by its shaft and the disk D⁴. These feed-rolls D and D' are so proportioned that the fabric delivered by one entire revolution is one yard in length. The pin D³ operates in its passage the swinging lever L, the link L', and the bell-crank lever L², which in turn operates, through a link, L³, the lower die, H'. This forms the crease at b, Fig. 4, which in its turn becomes the fold at b², Fig. 1. The die K' of the set K K' is operated by the same pin, D³, Fig. 1, which acts, through the swinging lever M, the link M', the bell-crank M², and the link M³, so as to throw the die K' upward, which action will form a crease to correspond with the one shown at b', Fig. 1. These alternate creases in my machine are one-half a yard apart, so that the two folds of the bundle make a yard. The driving-wheel D of the sewing mechanism is driven by a belt, and the motion is transmitted to the other parts by the gears A², A³, and A⁴. (See Fig. 2.)

Having thus described my invention, what I 75 desire to secure by Letters Patent is—

1. The combination of the creasing-dies H H' with the link L³, bell-crank lever L², link L', swinging lever L, and pin D³, all operating together substantially as described, and for 80 the purpose set forth.

2. The combination of the creasing-dies K K' with the link M³, bell-crank lever M², link M', swinging lever M, and pin D³, all operating together substantially as described, and 85 for the purpose set forth.

THOMAS H. FARNHAM.
